GAITER

Leo Wiesenfeld, Brooklyn, N. Y.

Application April 24, 1936, Serial No. 76,160

8 Claims. (Cl. 36—2)

The present invention relates to gaiters or spats and has for its object to produce a gaiter which when worn will have the appearance of a conventional and standard form of gaiter.

- 5 A further object is to improve the fastenings by which the gaiter is held on the foot and to so construct them that each fastening will comprise a yieldingly extensible member independently removable when required.
- 10 A further object is to provide means whereby the fastenings may be quickly connected and disconnected and at the same time concealed when on the foot leaving exposed only the simulated buttons of one of the fastening members.
- 15 To the above ends the invention consists of the improved gaiter and the devices and combinations of devices as shown in the drawing and as hereinafter described and claimed.

The invention is shown in the accompanying drawing in which—

20 Fig. 1 shows in side elevation a gaiter embodying the invention;

Fig. 2 shows in full size a fragmentary portion of what will be referred to as the under flap, parts being broken away to show the underlying construction;

Fig. 3 shows a plan view, partially broken away, of one of the ball members of the fastenings and extensible connection;

30 Fig. 4 shows a horizontal section, very much enlarged, of portions of the overlapping flaps and the fastenings, the section being taken on the line 4—4 in Fig. 1, looking in the direction of the arrows in that figure;

35 Fig. 5 shows a sectional view taken on the line 5—5 in Fig. 2, also very much enlarged;

Fig. 6 shows in side elevation, somewhat enlarged, the device shown in Fig. 3.

Similar reference characters will be employed 40 to designate corresponding parts.

As usual in devices of this kind, the side opening is formed by what will be designated generally as flaps 1 and 2, the flap 1, which overlaps the flap 2, being specifically referred to as the 45 upper flap, and the flap 2 being specifically referred to as the under flap.

The upper flap 1 will be provided with a row of fastening members 3 permanently affixed thereto by the flanges 4 and the heads 5, the fabric of the flap 1 being provided with apertures to receive the socket members. The heads 5 which show on the outer surface of the flap 1 simulate 50 buttons, and if desired to still further simulate the ordinary button and button holes of the conventional gaiter, imitation button holes 6 may

be worked in the fabric projecting from the heads 5 forwardly, as indicated in Fig. 1. Upon the underside of the flap 1 the socket members will present the usual opening to receive the spherical head 7 of the cooperating fastening 5 members carried by the under flap 2.

The cooperating fastening members 7 are riveted or clamped in the usual way to the outer ends of elastic straps 8 which are formed of a continuous length of elastic webbing doubled 10 upon itself and engaging the slot 9 of a metal loop 10, said loop being provided with a hook 11 for a purpose to be hereinafter described.

The free ends of the straps 8 are held together by the clamping disks 12 and 13 by which the 15 ball members are secured thereto. Between the free ends of the elastic connections is a reinforcing metallic plate 14 through which passes the shank of the ball members of the fastening. As indicated in Fig. 3, this clamping plate extends 20 rearwardly from the ball members not only constituting a reinforcement which assists in holding the ball members to the elastic strap but also, as will be hereinafter set forth, constitutes a fulcrum to assist in disconnecting the members 25 of the fastenings, and also as a guide for the sliding movement of the ball members due to the elasticity of the straps to which they are connected when the gaiter is in use.

The under flap 2 is provided adjacent its free 30 edge with a plurality of aligned slots 15 through which the elastic connections 8 may be passed, thus bringing the ball members to the outer surface of the under flap 2, these slots also receiving and guiding the plates 14, as indicated in 35 dotted lines in Fig. 2 and as shown in Figs. 4 and 5. When thus inserted through the slots 15, the elastic connections will be upon the under surface of the flap 2 in position so that the hooks 11 may be engaged with metal loops 16 held by 40 textile loops 17 permanently secured in vertical alignment to the under surface of the flap 2 by means of a stay 18 which is stitched to the under surface of the flap 2, said stitching passing through the doubled textile loops 17. The row of 45 metal loops 16 are positioned rearwardly with relation to the row of slots 15 so that the elastic connections 8 when not under tension will permit the projection of the forward ends carrying the ball members normally to a point within the 50 edge of the under flap 2 and exposed on the upper or outer surface thereof to be engaged by the sockets upon the under surface of the upper flap.

The arrangement is such that when the fas- 55

tening members are engaged, as shown in Fig. 4, the ball members and extensible elastic straps will be covered by the upper flap 1, the socket members being so disposed with relation to the 5 edge of the upper flap 1 that the desired elastic play or stretch of the elastic connections 8 may be effected without moving the flap 1 a sufficient distance to expose any part of the fastenings or connections carried by the flap 2. Preferably the 10 under surface of the flap 2 will be provided with a pocket 19 formed by a strip of material 20 stitched along one edge as indicated at 21, and at its upper and lower edge as indicated at 22, with the inner edge 23 free, thus forming an 15 effective covering for the under surface of the attachments and fastening members carried by the under flap 2, while at the same time permitting access to the detachable hooks and loops by which the elastic connections 8 are held in 20 place.

The under surface of the upper flap 1 may, if desired, carry a flexible reinforcement 24 through which the socket members are passed and clamped and, if desired, a stay 25 may also be 25 employed to secure the reinforcement 24 adjacent the edge of the overlapping flap 1. The gaiter will of course be provided with any usual form of arch strap 26 passing under the foot in the usual manner.

30 In use the upper flap 1 will be brought over the edge of the under flap 2 and the ball and socket members of the fastenings will be snapped and coupled in the usual manner and, as before explained, the fastening of the overlapping flaps 35 of the gaiter will conceal all parts of the fastenings excepting the heads 5 of the socket members which will be exposed on the outer surface of the flap 1 to simulate buttons. In uncoupling the members it is only necessary to take hold of 40 the outer flap 1 near the top, and pull forward thereon. This will disconnect the ball and socket fastenings and that result is greatly facilitated by reason of the plates 14 which, as before stated, act as fulcrums and provide considerable lever- 45 age, resisting the bending movement of the ball members which might result from the forcing forwardly of the edge of the flap 1, thus causing the ball members to snap out of the socket members rather freely under the strain imparted to 50 the edge of the upper flap 1. The arrangement of course forms a secure but yielding connection and one in which independent ball members may be removed and replaced as required, either for 55 cleaning the gaiter or for inserting new elastic connections, and while they are each free to yield under the stress produced by the bending of the ankle while walking, nevertheless the character of the fastenings will be effectually covered and hidden by the overlapping outer flap.

60 I claim:

1. A gaiter or spat comprising overlapping flaps, the outer flap being provided upon its outer surface parallel to its edge with a row of simulated buttons each carrying a socket member at 65 its inner face, said socket member opening upon the under surface of the outer flap, the inner flap being provided with a row of ball members positioned upon its outer surface adjacent to but wholly within the edge thereof to be engaged 70 with the socket members of the outer flap, each of said ball members being secured to the outer end of one of a group of independent elastic straps mounted upon the under surface of the inner flap and each of said straps being inde-

pendently and detachably connected at its inner end to the inner flap.

2. A gaiter or spat comprising overlapping flaps, the outer flap being provided upon its outer surface parallel to its edge with a row of simulated buttons each carrying a socket member at 5 its inner face, said socket member opening upon the under surface of the outer flap, the inner flap being provided with a row of ball members positioned upon its outer surface adjacent to but wholly within the edge thereof to be engaged with the socket members of the outer flap, each of said ball members being mounted on the outer end of one of a group of independent elastic straps mounted upon the under surface of the 10 inner flap and each being independently and detachably connected at its inner end with the inner flap; the inner flap being provided with aligned slots adjacent its free edge with the ends of the 15 elastic straps and the ball members extended through and beyond said slots from the inner to the outer surface and means to stiffen said elastic straps to guide their movement through the slots.

3. A gaiter or spat as defined in claim 2, in which the stiffening means is carried by the elastic straps with the ball members secured thereto, said stiffening means extending through said slot and rearwardly of the ball members.

4. A gaiter or spat comprising overlapping flaps, the outer flap being provided upon its outer surface parallel to its edge with a row of simulated buttons each carrying a socket member at 30 its inner face opening upon the under surface of the flap, the inner flap being provided with a row of ball members exposed upon its outer surface adjacent to but wholly within the edge thereof to be engaged with the socket members of the outer flap, each of said ball members being mounted on the outer end of one of a group of independent elastic straps mounted upon the 35 under surface of the inner flap and each being detachably connected at its inner end with the inner flap; the ball members being normally positioned closely adjacent to but within the edge of the inner flap with the edge of the outer 40 flap extending rearwardly beyond the socket members when overlapping the inner flap to cover and hide the ball members and the straps carried by the inner flap while permitting extensible movement thereof.

5. A gaiter or spat comprising overlapping flaps, the outer flap being provided upon its outer surface parallel to its edge but at a substantial distance therefrom with a row of simulated buttons, each provided with one member of a fastener disposed upon the inner surface of the outer flap, the inner flap being provided with a 55 row of complementary fastener members, each of said members being mounted on one of a group of independent elastic extensible connections independently and detachably connected to the inner flap at their inner ends.

6. A gaiter or spat comprising overlapping flaps, the outer flap being provided upon its outer surface parallel to its edge but at a substantial 60 distance therefrom with a row of simulated buttons, each provided with one member of a fastener disposed upon the inner surface of the outer flap, the inner flap being provided with a row of complementary fastener members, each of said members being mounted on one of a group of independent elastic extensible connections independently and detachably connected to the inner flap at their inner ends, with the 65 edge of the outer flap extending rearwardly be- 70 75

yond the fastener members and simulated buttons to cover and protect the complementary fastener members and the extensible connections thereof while permitting the extensible movement thereof when the fastener members are connected with each other.

7. A gaiter or spat comprising overlapping flaps, one of the flaps being provided with independent elastic straps, a fastener member at 10 the outer end of each of said straps and independently detachable connections at the inner end of said straps to attach said straps to the flap, and fastener members carried by the other flap to be engaged by the fastener members carried by the elastic straps, said fastener members being so positioned with relation to the edges of the overlapping flaps as to be entirely concealed when connected with each other.

8. A gaiter or spat comprising overlapping 20 flaps, the outer flap being provided upon its outer surface parallel to its edge with a row of

simulated buttons each carrying a socket member at its inner face, said socket member opening upon the under surface of the outer flap, the inner flap being provided with a row of ball members positioned upon its outer surface adjacent to but wholly within the edge thereof to be engaged with the socket members of the outer flap, each of said ball members being mounted on the outer end of one of a group of independent elastic straps secured to the under surface of the inner flap at their inner ends, the inner flap being provided with aligned slots adjacent its free edge with the ends of the elastic straps carrying the ball members extended through and beyond said slots from the inner to the outer surface of said flap and having a sliding movement therein, and stiffening and reinforcing plates secured to said elastic straps to guide the sliding movement of the straps through the slots.
